[57] **CLAIM**

The ornamental design for a hand-held labeler, as shown and described.

DESCRIPTION

FIG. 1 is a perspective view of a hand held labeler showing our new design;

FIG. 2 is a side elevational view thereof;

FIG. 3 is the opposite side of FIG. 2;

FIG. 4 is a top plan view thereof;

FIG. 5 is a bottom plan view thereof;

FIG. 6 is a front elevational view thereof;

FIG. 7 is a rear elevational view thereof;

FIG. 8 is an additional perspective view from the bottom, side and front thereof;

FIG. 9 is a perspective view of a second embodiment of FIG. 1;

FIG. 10 is a side elevational view of FIG. 9;

FIG. 11 is the opposite side of FIG. 10;

FIG. 12 is a top plan view of FIG. 9;

FIG. 13 is a bottom plan view of FIG. 9;

FIG. 14 is a front elevational view of FIG. 9;

FIG. 15 is a rear elevational view of FIG. 9; and,

FIG. 16 is an additional perspective view from the bottom, side and front of FIG. 9.
